UNITED STATES PATENT OFFICE.

FREDERICK H. OBERSCHMIDT, OF CLEVELAND, OHIO, ASSIGNOR TO THE CUTLER-HAMMER MFG. CO., OF MILWAUKEE, WISCONSIN, A CORPORATION OF WISCONSIN.

ELECTRICAL CONTROLLER FOR MOTOR-DRIVEN DEVICES.

Application filed April 28, 1924. Serial No. 709,356.

To all whom it may concern:

Be it known that I, FREDERICK H. OERSCHMIDT, a citizen of the United States, residing at Cleveland, in the county of 5 Cuyahoga and State of Ohio, have invented new and useful Improvements in Electrical Controllers for Motor-Driven Devices, of which the following is a full, clear, concise, and exact description, reference being 10 had to the accompanying drawing, forming a part of this specification.

This invention relates to improvements in electrical controllers for motor driven devices and is applicable particularly to 15 rubber mill and analogous controllers.

In control of motor driven rubber mills and other mechanisms where provision for quick stopping of a high inertia load is essential it is customary to provide readily 20 accessible means operable for deenergization of the driving motor and practically simultaneous application of a powerful brake.

The present invention has among its objects that of providing improved and simplified apparatus for the foregoing and other 25 purposes.

Another object is that of providing against energization of the motor except while the brake is released.

Another object is that of providing exceedingly simple, rugged and reliable apparatus for such purposes and whereof the electrical energy consumption for control 30 purposes is minimized.

Other objects and advantages will hereinafter appear.

The accompanying drawing, consisting of a single figure, illustrates diagrammatically and schematically, a proposed embodiment 40 of the invention.

Referring to the drawing, the same illustrates a roller 5, indicating a portion of a rubber mill or the like, driven by a motor 6, the latter to be suitably supplied with electrical energy as from lines L^1 L^2 L^3 subject to energization control as by manually operable switch 7. Said switch is provided with a hold-in latch 8 biased to releasing position and having electromagnetic means 45 comprising a coil 9 for holding the same in latching relation subject to release upon deenergization of said coil due to interruption of its circuit, failure of the supply vol-

tage or other cause. Suitable starting means is provided for the motor, which means may 55 preferably comprise an auto-transformer type starter as shown.

A mechanical brake 10 having a suitable cylinder 11 is provided for the roller 5, said brake being of relatively high power to 60 overcome rapidly the inertia of the roller and also of the rotor and associated parts assuming direct or positive drive of the former by the latter.

In practice the required brake-engaging force is so large as to render electromagnetic release of the brake uneconomical and hence undesirable. The brake, however, is provided with an electromagnetically engageable latch 12 for holding the same released 65 following manual release thereof, said latch being biased out of holding relation as by a spring 13 and being provided with a coil 14 adapted when energized to project the latch into holding position against the 70 action of said spring. Further the relation is such as to permit manual release of the brake during energization of said coil.

The energizing circuit of switch holding or latching-in coil 9 is connected as shown 75 to be capable of energization only upon closure of switch 7. Also said circuit is provided with a normally open interlocking switch 15 to be closed and held closed upon and during released positioning of the 80 brake.

The energizing circuit of brake release latching coil 14 is arranged to be energized 85 irrespective of the position of switch 7.

Jointly operable safety switches 16 and 17 90 are arranged in the respective energizing circuits of each of said coils 9 and 14, said switches having common operating means which may preferably comprise a cradle type actuator 18 arranged above the roll 5 95 and within easy reach of the operator.

Upon actuation of said cradle both of said switches 16 and 17 are adapted to open, the switch 16 deenergizing coil 9 for opening of switch 7 and deenergization of the 100 motor, and the switch 17 similarly deenergizing coil 14 to thereby permit withdrawal of latch 12 and resultant application of the brake for quick stopping of the roller. Such application of the brake results in opening 105 of switch 15.

Following such stopping, switch 7 cannot be electromagnetically latched in closed position except following release of the brake and consequent closure or resetting of switch 15, such arrangement practically insuring against operation of the motor except when the brake is released. It is apparent that following failure of voltage of the supply lines the interlocking switch 15 also serves as described to prevent operation of the motor except while the brake is fully released.

What I claim as new and desire to secure by Letters Patent is:

- 15 1. In a controller for motor driven rubber mills and the like provided with suitable brakes, the combination with individual electroresponsive means to respectively control energization of the motor and application of the brake, of interlocking means providing against electromagnetically controlled energization of the motor except under conditions of release of the brake. 2. In a controller for motor driven rubber mills and the like provided with suitable brakes, the combination with a motor circuit controlling switch having electroresponsive means adapted when energized to hold the same in closed position and a brake having electroresponsive means for latching the same in released position, of means controllable by said brake to prevent actuation of said latching-in means except during maintenance of said brake in released position. 3. In a controller for motor driven rubber mills and the like provided with suitable brakes, the combination with a switch having electroresponsive latching-in means to control the motor circuit and a brake having electroresponsive means for latching the same in released position, of voluntarily operable means for interrupting the energizing circuits of said electroresponsive means to thereby cause interruption of the drive and application of the brake, said voluntarily operable means being biased to resetting position, and means associated with said brake to require release thereof prior to energization of said latching-in means for said switch. 4. In a controller for motor operated rubber mills and the like, the combination with a switch to control energization of the motor and electroresponsive latching-in means for said switch, of a brake, electroresponsive means for holding the brake released and adapted when deenergized to cause application of the brake, a normally open switch arranged to control energization of said latching-in means and operating means providing for closure of said switch upon release of the brake and opening of the former upon application of the latter. 5. In a controller for motor driven rub-

20 25 30 35 40 45 50 55 60 65 70 75 80 85 90 95 100 105 110 115 120 125 130 135

1. In a controller for a motor driven rubber mill or the like, the combination with a circuit for the motor, a switch biased to open position, said switch being manually operable to close said circuit, electroresponsive means adapted when energized to hold said switch in closed position, a manually releasable brake and a latch for holding the same in released position, said latch being biased into retracted position, and electroresponsive means adapted when energized to project said latch, said last mentioned electroresponsive means being energizable independently of said first mentioned electroresponsive means, energization of said first mentioned means being dependent upon movement of said brake to released position. 7. In a controller for a motor driven rubber mill or the like, the combination with a circuit for the motor, a switch biased to open position, said switch being manually operable to close said circuit, electroresponsive means adapted when energized to hold said switch in closed position, a manually releasable brake and a latch for holding the same in released position, said latch being biased into retracted position, electroresponsive means adapted when energized to project said latch, said last mentioned electroresponsive means being energizable independently of said first mentioned electroresponsive means, energization of said first mentioned means being dependent upon released positioning of said brake; and voluntarily operable means for effecting substantially simultaneous interruption of the circuits of said electroresponsive means. 8. In a controller for a motor driven rubber mill or the like, the combination with a circuit for the motor, a switch biased to open position, said switch being manually operable to close said circuit, electroresponsive means adapted when energized to hold said switch in closed position, a manually releasable brake and a latch for holding the same in released position, said latch being biased into retracted position, electroresponsive

sive means adapted when energized to project said latch, said last mentioned electro-responsive means being energizable independently of said first mentioned electro-responsive means, energization of said first mentioned means being dependent upon released positioning of said brake, and a plu-

rality of normally closed safety switches having common operating means for effecting simultaneous deenergization of said electroresponsive means. 10

In witness whereof, I have hereunto subscribed my name.

FREDERICK H. OBERSCHMIDT.
